MARINE PROPULSION.

1,286,625.

Specification of Letters Patent.

Patented Dec. 3, 1918.

Application filed February 11, 1916. Serial No. 77,702.

To all whom it may concern:

Be it known that I, HERBERT T. HERR, a citizen of the United States, and a resident of Pittsburgh, in the county of Allegheny and State of Pennsylvania, have made a new and useful Invention in Marine Propulsion, of which the following is a specification.

This invention relates to turbine installations, and particularly to organized power producing apparatus suitable for use in marine propulsion.

An object of the invention is to produce an organized turbine apparatus, which is capable of operating efficiently under widely varying loads and at different speeds.

In battleship construction it is necessary to maintain the efficiency of the power developing apparatus at high speed and also at cruising or low speed, and an object of my invention is to produce a power developing apparatus which fulfills this requirement.

A further object is to produce a power developing apparatus, suitable for ship propulsion in which means are employed for obtaining high economy while the apparatus is operating not only at high and at low speeds but also at determined intermediate speeds.

These and other objects, which will be made apparent throughout the further description of the invention, are attained by means of apparatus embodying the features herein described and illustrated in the drawings accompanying and forming a part hereof.

In the drawings, Figures 1 and 2 are diagrammatic illustrations of different embodiments of my invention.

In Fig. 1, I have illustrated an apparatus which is capable of maintaining high economy, while operating under widely varying power and speed conditions. As illustrated, the apparatus is adapted to drive a single propeller shaft 3 and includes a turbine unit, generally illustrated at 4, which is divided into two sections, an initial section 5 and a low pressure section 6, both of which are geared to the propeller shaft 3 by means of a reduction gearing 7. The apparatus also includes a cruising element 8 which, under certain power and speed conditions, is adapted to operate in series with the initial section 5 of the turbine unit 4. As illustrated, this element is geared to the shaft of the section 5 by means of a reduction gearing 9,

so that it operates through double reduction gearing, in delivering power to the propeller shaft 3.

The turbine unit 4 illustrated corresponds in essential details to the turbine disclosed in Patent No. 1,155,516 of October 5, 1915, issued to Henry F. Schmidt of Pittsburgh, Pa. The initial section includes a high pressure stage 10, which receives motive fluid from a conduit 11, and which is adapted to deliver the motive fluid, issuing from it, to intermediate and low pressure elements included within the initial section. The intermediate and low pressure elements are adapted to expand fluid received by them to exhaust pressure and consequently the section 5 is shown equipped with a condenser 12, which communicates with exhaust passages formed in both ends of the turbine section. The exhaust passage at the admission end of the section communicates with a reversing element, diagrammatically shown at 13, which is adapted to receive motive fluid from a conduit 14 and which is separated from the ahead portion of the turbine elements by a packing or seal, such as is ordinarily employed in turbine construction.

The fluid issuing from the initial or high pressure stage 10 of the section 5 is also adapted to be divided into two streams, one of which, as has been described, passes through the low pressure elements of the section 5, while the other is delivered through a conduit 15 to the low pressure section 6. The low pressure section is illustrated as a double flow turbine and consequently the fluid delivered to it by the conduit 15 is divided into two separate streams which pass through the bilaterally symmetrical working passages of that section. The section 6 is adapted to expand the motive fluid received by it to exhaust pressure and is served by a condenser 16. With this arrangement, the motive fluid delivered from the high pressure stage 10 of the section 5 is divided into three separate streams; or, in other words, the turbine unit 4 is provided with three low pressure elements, through which the steam issuing from the high pressure stage passes in parallel. As described in the Schmidt patent, above referred to, the initial section 5 is designed to operate with highest efficiency under different speed conditions from those for which the turbine 6 is constructed, although the efficiency of the

unit is high when the apparatus is operating at the speed for which the low pressure section is primarily constructed.

As illustrated, the initial section 5 is directly connected to a pinion 18, which meshes with the large gear 19 of the gearing 7. The section 6 is operatively connected to a pinion 20 by means of a disconnectible coupling or clutch 21. The pinion 20 also meshes with the gear 19. While developing full power both the sections 5 and 6 are operatively connected through the gearing 7 to the propeller shaft 3 and motive fluid is delivered to both sections, as has been previously described. Under such conditions, both condensers 12 and 16 are in operation and the gearing 9 is preferably disconnected from the shaft of the section 5, a disconnectible clutch or coupling 22 being employed for this purpose.

At reduced speed, for example, at two-thirds speed, the conduit 15 is closed by means of a valve 23 and the clutch 21 is thrown out. This renders the low pressure section 6 inoperative as a power developing agent, and the propeller shaft receives power from the section 5 only, and the condenser 16 may be shut down.

At a lower speed, the cruising element operates in series with the section 5. This cruising element may be of any type, and while operating in series with the section 5, is adapted to partially expand the motive fluid before delivering it to that section. As illustrated, the conduit 11 is provided with a valve 25, and a bypass is provided around the valve which includes the cruising element 8, a valve inlet pipe or passage 26, which receives fluid from the conduit 11 on the supply side of the valve 25, and a valved discharge pipe or passage 27 which communicates with the conduit 11 on the delivery side of the valve 25. With this arrangement the section 5 receives low pressure or expanded fluid from the element 8 and power is delivered to the shaft 3 by the element 8 through the reduction gearings 7 and 9 and by the section 5 through the single reduction gearing 7.

As an alternative arrangement, I have shown at 28 a valved connection between the section 8 and the condenser 12. This connection will only be open when the valve in the discharge pipe or passage 27 is closed and consequently the cruising element 8 could, under emergency or under certain speed and power conditions, operate independently of the section and whether that section were receiving high pressure fluid or not. I have also illustrated a valved pipe or passage 29 for delivering high pressure motive fluid to the low pressure section 6 in case of an emergency or in case the section 5 is incapacitated. While this pipe or passage is delivering motive fluid to the section

6, the valve 23 in the passage 15 will of course be closed, and the section 6 may operate independently of or in conjunction with the section 8.

In Fig. 2, I have illustrated an embodiment of the invention in which two turbine units, similar to the unit 4, are employed and in which one section of one of these units is capable of operating in series with one section of the other unit. As illustrated, the propeller shaft 3 is provided with a gearing 7 for operatively connecting the sections 5' and 6' of a turbine unit 4' to it. The sections 5' and 6' are similar to the respective sections 5 and 6 of Fig. 1 except, as illustrated, both sections are served by the same condenser 30.

In this embodiment of the invention, the cruising element 8 of Fig. 1 is replaced by the turbine unit 31, which delivers power to the shaft 3 through double reduction gearing, (viz. the gearing 7 and a gearing 36), and which, like the unit 4', is formed in two sections, 32 and 33. The initial section 32 of this unit is similar in structural details to the section 5 of Fig. 1 and is adapted to deliver approximately two-thirds of the steam issuing from its high pressure stage to the low pressure section 33. As described in connection with the unit 4', both the sections 32 and 33 may be served by a single condenser 34, although it is desirable to provide a separate valve between the exhaust of each section and the condenser. The section 32 is shown directly connected to a pinion 35, which meshes with a gear 36^a coupled, by means of a disconnectible coupling or clutch 37, to the shaft of the section 5'. The section 33 is shown coupled, by means of a clutch 38 to a pinion 39, which also meshes with the gear 36^a. The gear 36^a and pinions 35 and 39 comprise the reduction gearing 36.

A cruising element 40 is shown operatively connected to the shaft of the section 32 by means of a reduction gearing 41 and a disconnectible coupling or clutch 42. This element is adapted to receive motive fluid from a conduit 11' which supplies the section 5' and also the section 32. It is also adapted to return fluid to the conduit 11' and for this purpose a valve 43 is provided in the conduit 11' around which fluid, delivered to the element 40, is bypassed. A similar construction is employed in connection with the section 32 and, as illustrated, a valve 44 is provided in the conduit 11', on the inlet side of which a valved inlet pipe 45 is located, while on the delivery side a valved discharge pipe 46 is located, both these pipes communicating with the section 32, and also with the conduit 11'.

Under full power conditions both the turbine units 4' and 31 receive motive fluid, the valves 43 and 44 being open, the valves 130

in the inlet and exhaust pipes communicating with the element 40 being closed, and the valve in the exhaust pipe 46 being closed. The clutches 21' and 37 are both in and the 5 clutch 42 is out. Under such conditions, both the units 4' and 31 operate as independent turbine units, the one delivering power to the shaft 3 through the reduction gearing 7 and the other delivering power to the 10 shaft through the reduction gearing 36 and the gearing 7.

For the purpose of reducing the power delivered to the propeller shaft and consequently the speed of the shaft, the section 6' 15 may be cut out of operation by closing the valve in the pipe 15' and by throwing out the clutch 21'. A further reduction in power may be accomplished by throwing out the clutch 38 and cutting off the steam supply to the section 33. Under such conditions 20 both sections 5' and 32 operate as independent turbines, each being served by a separate condenser. For a further reduction in power, the section 32 may be cut 25 out and the clutch 37 thrown out. For a still further reduction of power, the section 32 may be operated in series with the section 5'. This is accomplished by closing the valve 44, opening the valve 30 in the discharge pipe 46, and closing communication between the section 32 and the condenser 34, it being understood that communication between the section 33 and the condenser may be shut off when the 35 section 33 is not in operation. Fluid delivered to the section 32 will, after having traversed that section, be redelivered to the conduit 11' and by the conduit to the section 5'. For a still further reduction in power 40 the cruising element 40 will be brought into operation, so that it operates in series with both the sections 32 and 5'. This is accomplished by closing the valve 43 and opening both the valves in the inlet and 45 exhaust pipes communicating with the element 40. The clutch 42 will also be thrown in, so that the gearing 41 is operatively coupled to the shaft of the section 32. The fluid delivered to the section 40 is partially 50 expanded in that section, is returned to the conduit 11' on the delivery side of the valve 43 and is delivered to the section 32, where it is further expanded in doing work in that section. The fluid is then delivered to the 55 section 5', as has already been described. Each of the elements 40, 32 and 5' will then deliver power to the propeller shaft 3; the first through the reduction gearings 41, 36, and 7, the second through the reduction 60 gearings 36 and 7, and the third through the single reduction gearing 7. It will be apparent to those skilled in the art that the best economy for low speed conditions may be obtained by designing the initial sections 65 of the units 4' and 31 so that they will de-

velop highest efficiency while operating at certain reduced speeds. It will also be apparent that under certain power conditions it may be desirable to bypass the fluid delivered to the section 5' from the section 32 70 around the high pressure stage of the section 5'. It will also be apparent that the turbine unit 31 may be duplicated and so arranged that the duplicate units may be operatively connected by means of a reduction gearing to the shaft of the turbine section 6' or that the cruising element 40 may be replaced by an additional turbine unit similar to the unit 31 and that an additional 75 cruising element may be employed. With such an arrangement, various combinations 80 of elements may be obtained which will operate with high efficiency at various intermediate speeds and consequently the propelling apparatus will develop high economy 85 while operating at a number of different determined speeds.

While I have illustrated but two embodiments of my invention, it will be apparent to those skilled in the art that various modifications, substitutions, additions and omissions may be made in the apparatus illustrated without departing from the spirit and scope of my invention, as set forth by the appended claims. 95

What I claim is:

1. An organized turbine apparatus, comprising a turbine unit divided into two sections, one of which receives partially expanded motive fluid from the other, a driven 100 agent, independent means for operatively connecting each turbine section to the driven agent, and an independent turbine element adapted to deliver partially expanded motive fluid to one section of the turbine unit, under 105 low power and low speed conditions, and to operate in parallel with the divided turbine unit under maximum speed conditions.

2. An organized turbine apparatus comprising a turbine unit, divided into an initial 110 and a low pressure section, a driven agent, means for operatively connecting each section to the agent while the unit is developing full power, and for operatively disconnecting the low pressure section from the agent 115 while the turbine unit is developing reduced power, an independent turbine element, adapted to deliver partially expanded motive fluid to the initial section while the apparatus is developing relatively low power 120 and operating at slow speed, a reduction gearing operatively connecting the shaft of the turbine element to the shaft of the initial section, a condenser serving the low pressure section of the divided unit, and a separate 125 condenser serving the initial section so that said initial section may be operated independently of the low pressure section.

3. An organized power developing apparatus, comprising a driven agent, two power 130

developing units, adapted to operate in parallel under full power conditions, a single reduction gearing between one of said units and said agent, and double reduction gearing between the other unit and the agent.

4. An organized power developing apparatus, comprising a driven agent, two turbine units, one of said units being formed in two sections, each section being capable of 10 independent operation, means for delivering partially expanded motive fluid from the other unit to one of said sections, and a double reduction gearing between said last mentioned unit and the driven agent.

15. 5. An organized power developing apparatus, comprising a driven agent, a turbine unit, divided into an initial and a low pressure section, said low pressure section receiving partially expanded motive fluid from the 20 initial section, means for independently operatively connecting said sections to said agent, means whereby said sections may be operated independently of each other, a second turbine unit, adapted to deliver partially 25 expanded motive fluid to said initial section, and a reduction gearing between said second unit and said agent.

6. An organized power developing apparatus, comprising a driven agent, a turbine 30 unit divided into two sections, one receiving partially expanded fluid from the other, a turbine element adapted, under certain power and speed conditions, to operate in series with one of said sections and under 35 other power and speed conditions to operate in parallel with said sections, and reduction gearings so arranged that each section delivers power to said agent through a single reduction and said element delivers power to 40 said agent through a double reduction.

7. An organized power developing apparatus comprising a driven agent, a turbine unit divided into an initial section, and a low pressure section operating in parallel 45 with low pressure elements of the initial section on motive fluid delivered from a high pressure stage of the initial section, a second turbine unit adapted under certain speed and power conditions to operate in series 50 with the initial section of said first mentioned unit, and speed reduction mechanisms and couplings so arranged that said second unit and either or both of said sections may be operatively connected to said agent.

55. 8. An organized power developing appa-

ratus, comprising a driven agent, a turbine unit divided into an initial and a low pressure section, each of which expands motive fluid to exhaust pressure and the low pressure section of which receives partially expanded motive fluid from the initial section under full power conditions, and means for operatively connecting each section to said agent while the unit is developing full power, in combination with an independent 65 turbine unit adapted to deliver partially expanded motive fluid to the initial section while the apparatus is developing reduced power and to fully expand motive fluid under conditions of excessive load, and a 70 speed reducing mechanism between said element and a section of said unit.

9. An organized power developing apparatus, comprising a driven agent, a turbine unit formed in two sections, speed reducing mechanism between each of said sections and said agent, a second turbine unit divided into two sections, speed reducing mechanism between said last mentioned sections and one section of said first mentioned unit, and means for operating one section of one unit in series with one section of the other unit. 75

10. An organized power developing apparatus, comprising a driven agent, two power developing units adapted to operate in parallel under full power conditions and in series under reduced power conditions, a single reduction gearing between one of said units and said agent, and a double reduction gearing 80 between the other unit and said agent. 90

11. In an organized power developing apparatus, a driven agent, a turbine unit comprising an initial section, and a low pressure section adapted to operate in parallel with low pressure elements of the initial section on steam discharged from a high pressure stage of the initial section, a speed reducing mechanism between each section and the driven agent, a third turbine section adapted under certain power conditions 100 to deliver partially expanded steam to a high pressure stage of the initial section and a speed reducing mechanism between said third section and the initial section of said unit. 95

In testimony whereof, I have hereunto subscribed my name this 9th day of February, 1916.

HERBERT T. HERR.
